CLAIM

The ornamental design for a cutting board, as shown and described.

DESCRIPTION

FIG. 1 is a front and side perspective view of a cutting board showing our new design;

FIG. 2 is a front view thereof;

FIG. 3 is a back view thereof;

FIG. 4 is a side view thereof;

FIG. 5 is a side view thereof which is opposite the view of FIG. 4;

FIG. 6 a top view thereof based upon the orientation of FIG. 1; and,

FIG. 7 is a bottom view thereof based upon the orientation of FIG. 1.

The areas shown in broken lines show environmental structure and form no part of the claimed design.
